UNITED STATES PATENT OFFICE.

HARRY G. TRAVER, OF NEW YORK, N. Y., AND CHARLES W. NICHOLS, OF NEWARK, NEW JERSEY, ASSIGNEES TO TRAVER CIRCLE SWING CO., A CORPORATION OF NEW YORK.

AMUSEMENT APPARATUS.

SPECIFICATION forming part of Letters Patent No. 758,341, dated April 26, 1904.

Application filed October 3, 1902. Serial No. 125,725. (No model.)

To all whom it may concern:

Be it known that we, HARRY G. TRAVER, residing in the borough of Manhattan, city, county, and State of New York, and CHARLES W. NICHOLS, residing at Newark, in the county of Essex and State of New Jersey, citizens of the United States, have invented certain new and useful Improvements in Amusement Apparatus, of which the following is a specification, reference being had therein to the accompanying drawings, which form a part thereof.

Our invention relates to amusement apparatus, and more particularly to a class thereof analogous to the well-known type of round-about.

The object of the invention is to provide an amusement apparatus of this type wherein the cars and occupants will be forced to travel in a path of gradually-increased radius and altitude, whereby the occupants will receive in addition to the pleasurable sensation of the ordinary roundabout those attendant upon the increased speed and the gradual rise from and return to the ground or starting-level.

A further object is to provide an apparatus of this type the use of which will be attended with no extraordinary dangers to life or limb and which will be furnished with a variety of safety appliances; to guard against the accidental and violent return of the cars to the starting-level while the device is in operation; to overcome the effects of the contact of the cars with the ground or other abutment at the starting-level when returning to rest under normal conditions; to avoid the dangers through the breakage of the main suspension cables and those possibly attendant upon any unequal distribution of the load, the individual sagging of any one of the radial supporting-arms, or wear on the bearings of the main shaft.

A still further object is to provide means whereby the apparatus may be kept under perfect control and the rotary movement may be so controlled as to avoid a sudden reduction of speed in or stoppage of the apparatus.

The invention consists in the combination, with a tower, a vertical shaft journaled therein and provided with a plurality of rotary radially-

projected arms, means for driving said shaft and means whereby said arms may rotate in one direction independently of said driving mechanism, of a plurality of cars suspended therefrom by means of a pivotal connection between the suspension means and the said arms whereby with the rotation of said arms centrifugal force will act to gradually force said cars outward radially of said arms and upward, and in such other novel features of construction and arrangement of parts as are hereinafter set forth and described, and more particularly pointed out in the claims hereto appended.

Referring to the drawings, Figure 1 is a view in elevation of the apparatus, showing the upper and the lower portion thereof only. Fig. 2 is a plan view of the lower portion thereof, the arrangement of the radially-projected arms being indicated in dotted lines; and Fig. 3 is a detail view of the running-gear and braking mechanism.

Like letters refer to like parts throughout the several views.

In the practice of our invention we employ a tower, as *a*, preferably of structural-steel work, suitably anchored and braced. At any desired point within this tower we arrange a horizontal platform *b*, upon which, if desired, may be located a gas engine, motor, or other source of power. (Not shown.) Journaled in a bearing on or adjacent to this platform is a vertical shaft *c*, which extends above the top of the tower *a*. This shaft is suitably braced at different points to prevent its springing or rotating out of true. The various bearings for this shaft *c* may be of any desired type; but we preferably employ ball or roller bearings. The portion of this shaft projecting beyond the top of the tower has rigidly attached thereto, so as to rotate therewith, a hub *d*, from which projects radially of the shaft *c* a plurality of arms arranged in pairs, as *d' d'*, *d'' d''*, *d''' d'''*. The members of these pairs of arms are disposed oppositely each other and are preferably of structural steel braced against lateral movement by means of the struts *e*. Suspended from these arms are a plurality of passenger baskets or cars *f*, each

- of which is made to possess considerable weight even when unloaded to insure stability of movement. The front of each car is arranged like the prow of a boat or else cigar 5 shaped to prevent as much as possible atmospheric resistance to the progress of the car through the air. The cars are suspended from the said arms by means of suspension-cables g g' , arranged in pairs adjacent to each 10 end of the car and attached thereto by means of eyebolts or other similar contrivances. As shown in the drawings, the cables at each side adjacent to one end of each car are secured to one of the radially-projected arms, as d' , while 15 the other pair are secured to the next succeeding arm, as d'' . The connections between these cables and their respective arms are preferably made by means of clevises; but other pivotal connections may be employed, 20 it being essential merely that these cables be permitted to swing outward radially of the shaft c . Each car is also provided with two additional cables, as g'' , similarly connected thereto and to the radial arms to take up the 25 strain in case of breakage or other accident to the main cables. These emergency-cables are secured at opposite ends of each car midway between the other cables. The lower edge of the inner side of each car is provided 30 with a spring-buffer f' , which preferably takes the form of a stiff leaf-spring, extending substantially the entire length of the car. When the cars are at rest—that is, upon the starting level—they preferably will be but a 35 few inches from the ground, and to facilitate the entrance and exit of passengers and also to prevent the cars swinging in against the tower structure the earth is banked up about the base thereof, as at j , or some other style 40 of buffer or abutment surrounding this base is provided to coöperate with the buffer-springs f' to take up the jar of the contact of the car and the abutment when the former comes to rest.
- 45 To prevent the occupants from leaving the car or exposing themselves to danger prior to the car reaching a state of complete rest, any suitable means of securing them therein may be employed, as in other amusement devices 50 of various classes.
- To guard against material oscillation of the hub d and its arms or the sagging of these arms individually, we provide a circular track h about the upper portion of the tower a and 55 equip each arm with a brace, as $h' h^4 h^5 h^6$, the lower portion of which is provided with an antifriction-roller i . This roller is normally out of contact with the track h , although it moves adjacent thereto and is adapted to 60 engage therewith with the slightest oscillation of the entire hub or any particular arm.
- The driving mechanism applied to the shaft c comprises a gear system, as k , actuated by any desired means and from any desired 65 source of power. The main gear k' of this

system encircles but is not attached directly to the shaft c , imparting movement thereto through a ratchet c' , carried by said shaft, and a pawl k^2 engaging therewith carried by the gear k' . This arrangement insures a smooth 70 rotation of the shaft c when power is applied through the gear k' and at the same time admits of the rotation of said shaft independently of said driving mechanism, an arrangement the necessity for which will appear hereinafter. 75

To bring the device to a state of rest, we provide a brake, as m , preferably of a type known as "roller-brakes," which is so adjusted as to be incapable of exerting sufficient braking force to suddenly bring the shaft to a dead stop. This brake is controlled by means of the hand-lever m' and a lever system m^2 between it and the frame m^3 carrying the rollers m^5 . 80 85

In the construction of the apparatus due attention must be given the direct vertical strain upon the arms d' , &c., as well as the horizontal strain thereon due to the centrifugal force exerted by the cars under all possible 90 conditions, as modified by the corresponding strain on the oppositely-disposed arms.

The operation of the device in so far as has not already been described is as follows: The shaft c being at rest and the cars all on the 95 starting-level adjacent to the embankment or abutment j , power is applied to the gearing k . As the gear k' thereof rotates the pawl k^2 picks up the shaft c by means of its ratchet c' . This rotates the hub d , the arms d' , d'' , d^3 , d^4 , d^5 , and d^6 , and the cars f suspended therefrom. Prior to the development of the 100 proper speed these cars have a slight tendency to swing toward the tower, and if they should contact therewith the spring-buffers f' will take up the jar of such slight contact with the bank or abutment j . As the number or revolutions per minute of the shaft c increases the cars f gradually swing outward away from the axis of said shaft and upward through the 110 well-known action of centrifugal force, and it will be observed that with this movement the radius of the path they follow gradually increases, so that the actual speed of the cars increases more through this movement than 115 by the actual increase in the number of revolutions of the shaft c . When the cars have reached the desired altitude, the speed of the driving mechanism is held there, and, if necessary, the brake m is applied to prevent the shaft 120 c exceeding this speed through momentum. This action is attended with perfect safety to the occupants of the cars, as the centrifugal force prevents their falling therefrom. The individual safety appliances, however, are provided to prevent needless exposure to personal danger through excitement, nervousness, or exhilaration. To restore the cars to the starting-level, it is necessary to gradually 125 reduce the number of revolutions of the 130

shaft c through momentum. This action is attended with perfect safety to the occupants of the cars, as the centrifugal force prevents their falling therefrom. The individual safety appliances, however, are provided to prevent needless exposure to personal danger through excitement, nervousness, or exhilaration. To restore the cars to the starting-level, it is necessary to gradually reduce the number of revolutions of the 130

shaft *c*. This is done by reducing the speed of the driving mechanism and by applying the brake *m*. If the power were shut off entirely, gravity would cause the cars to come into violent contact with the tower structure or through the great and sudden strain on the cables cause the breakage of said cables, and thus permit the cars to be projected from the supporting-arms tangentially to the circular course to the ground, as would a too great a reduction of speed of said mechanism or a powerful braking action, were it not that the shaft *c* is rotatable independently of said mechanism and that the brake *m* is purposely rendered incapable of exerting too great a pressure. With the arrangement substantially as shown and described if the power be entirely shut off the acquired momentum is sufficient to maintain, substantially, the same degree of centrifugal force independently of said driving mechanism, the ratchet *c'* and pawl *k*² facilitating this, and this force would be gradually exhausted through the load and the friction of the various parts. At any time the speed of the driving mechanism may be increased, and when it reaches or exceeds that of the shaft *c* it will automatically pick up the load. Hence, if desired, the speed of rotation may be changed to vary both the rate of travel and the altitude of the cars. The brake *m* may be applied by the operator to control the apparatus to a degree whereby it may be brought speedily to a state of rest; but being incapable of a braking power sufficient to bring the shaft to a dead stop such cannot result through accident. As the shaft *c* stops necessarily the cars will be subject to slight swinging movement, which will occasion contact thereof with the bank or abutment *j*. The spring-buffers *f'* take up the jar occasioned by such contact. The cars may be thus driven at a high rate of speed with few revolutions per minute of the shaft *c* and with the expenditure of but little power. This speed, it is apparent, may be increased by increasing the length of the arms *d'*, &c., or the height of the tower *a* and length of the suspension-cables. The increase and decrease of speed is gradual, and the apparatus is at all times under perfect control.

If through an unequal distribution of the load the hub *d* oscillates slightly, the shaft *c* should spring, or one of the arms should sag through weakness or breakage, some of the rollers *i* would immediately engage the track *h* and steady the entire device. If the main cables *g* *g'* should break, the emergency-cables *g*² would assume the burden of the car and prevent accident. The use of the apparatus is therefore attended with no unusual or extraordinary dangers. All bearings are preferably antifriction to insure a smooth action of the apparatus, particularly when coming to rest.

65 Preferably the tower *a* should be about

sixty feet in height and the arms *d'*, &c., about fifteen feet long, sufficient to clear the base of the tower and embankment or other abutment thereabout. We prefer to use cables for suspending the cars; but it is apparent that rods 70 might be substituted therefor without altering the operation of the device. The given proportions and details of construction, however, may be varied indefinitely without departing from the spirit or scope of our invention, and it is, therefore, not our intention to limit the invention to the details of construction as herein shown and described. 75

Having described the invention, what we claim as new, and desire to have protected by 80 Letters Patent, is—

1. In an amusement apparatus, the combination with a tower, a vertical shaft journaled therein, a plurality of radially-projected arms actuated thereby, stays connecting said arms, 85 and a driving mechanism rotating said shaft, of a plurality of cars, suspension-cables disposed on each side of and adjacent to each end of said cars respectively and means whereby the cables at the opposite ends of each car 90 are pivotally connected to succeeding radial arms whereby said cars under the influence of centrifugal force are permitted to swing outwardly radially of said shaft and upwardly. 95

2. In an amusement apparatus, the combination with a tower, a vertical shaft journaled therein, a plurality of radially-projected arms actuated thereby, stays connecting said arms, a brake acting on said shaft and so set as to have limited braking capacity and a driving 100 mechanism actuating said shaft, of a plurality of cars, suspension-cables disposed on each side of and adjacent to each end of said cars respectively, and means whereby the cables at the opposite ends of each car are pivotally 105 connected to succeeding radial arms whereby said cars under the influence of centrifugal force are permitted to swing outwardly radially of said shaft and upwardly.

3. In an amusement apparatus, the combination with a tower, a vertical shaft journaled therein, a plurality of radially-projected arms actuated thereby, stays connecting said arms, a driving mechanism rotating said shaft, means whereby said shaft is permitted to rotate in one direction independently of said driving mechanism and a brake acting on said shaft and so set as to have limited braking capacity, of a plurality of cars, suspension-cables disposed on each side of and adjacent to 110 each end of said cars respectively and means whereby the cables at the opposite ends of each car are pivotally connected to succeeding radial arms whereby said cars under the influence of centrifugal force are permitted 115 to swing outwardly radially of said shaft and upwardly. 120

4. In an amusement apparatus, the combination with a tower, a vertical shaft journaled therein, a plurality of radially-projected arms 125

actuated thereby, stays connecting said arms, and a driving mechanism rotating said shaft, of a plurality of cars, suspension-cables disposed on each side of and adjacent to each 5 end of said cars respectively, means whereby the cables at the opposite ends of each car are pivotally connected to succeeding radial arms whereby said cars under the influence of centrifugal force are permitted to swing outwardly radially of said shaft and upwardly 10

and spring-buffers disposed on the side of each car toward the tower.

In witness whereof we have hereunto affixed our signatures this 29th day of September, 1902.
